US0D1062449S

(12) **United States Design Patent** (10) Patent No.: **US D1,062,449 S**
(45) Date of Patent: ** Feb. 18, 2025

(54) **PACKAGING BOX**

(71) Applicant: **Shenzhen Yingfeng Intelligent Technology Co., Ltd.**, Shenzhen (CN)
(72) Inventors: **Suhua Tian**, Shenzhen (CN); **Zhe Wang**, Shenzhen (CN); **Baoya Wang**, Shenzhen (CN)

(**) Term: **15 Years**

(21) Appl. No.: **35/519,376**

(22) Filed: **Jul. 19, 2023**

(80) **Hague Agreement Data**

Int. Filing Date: **Jul. 19, 2023**

Int. Reg. No.: **DM/233643**

Int. Reg. Date: **Jul. 19, 2023**

Int. Reg. Pub. Date: **Dec. 15, 2023**

(51) **LOC (15) Cl.** 09-03

(52) **U.S. Cl.**

USPC **D9/430**

(58) **Field of Classification Search**
